DOOR LOCK

Charles S. Bock, Chicago, Ill., assignor to Andrew Hoffman, Chicago, Ill.

Application November 22, 1941, Serial No. 420,105

5 Claims. (Cl. 70—92)

My invention relates to door locks, and more particularly to the type called panic locks and used for escape purposes in schools, factories, etc., in case of fire or other emergency. Locks of the type under consideration are usually made in right and left hand forms, so as to be applicable according to the location of the closing side of the door. Or, certain parts of the locks are designed in alternative forms, to make either form available according to the type of lock installation. These characteristics make universal locks more expensive, requiring both forms of the lock or parts thereof to be available in stock at all times in order to supply orders for one form or the other.

In view of the foregoing condition, my main object is to provide a lock which is constructed as a unit for use either in the right-hand or left-hand position, whereby to make a single form of lock serve both purposes.

A further object of the invention is to provide a lock in which no change whatever need be made in order to adapt it to either the right-hand or left-hand position.

Another object of the invention is to provide a lock which has few parts, and is therefore extremely simple.

With the above objects in view, and many others which may suggest themselves from the description to follow, a better understanding of the invention may be had by reference to the accompanying drawings, in which—

Fig. 1 is a fragmentary elevation of a door which closes at the right-hand side, showing one form of the improved panic lock mounted thereon;

Fig. 2 is a similar view showing the lock inverted and mounted on a door closing at the left-hand side;

Fig. 3 is an enlarged elevation of the lock shown in Fig. 1, partly broken away;

Fig. 4 is a section on the line 4—4 of Fig. 3, partly broken away;

Fig. 5 is an interior view of a modification, with a portion of the cover removed;

Fig. 6 is a section on the line 6—6 of Fig. 5 and showing the cover; and

Figs. 7 and 8 are, respectively, enlarged sections on the lines 7—7 and 8—8 of Fig. 5.

As is well known, a fire or emergency door always opens outwardly. The application of a panic lock prevents the door from being drawn open from the outside, but enables it to be pushed open from the inside when pressure against a lever is applied. While a panic lock could be

mortised or otherwise encased within the door, it is a more simple matter to make the lock as a separate unit and apply it directly to the inner side of the door.

Specific reference to the drawings indicates the casing of the improved lock at 10, such casing having a base 11 which is secured to the inner side of the door 12 by means of screws 13. I have also shown a keeper unit 14 mounted on 10 the jamb or door frame 15 at a point opposite the lock 10, the keeper unit also having a base 16 which is secured to the jamb or door frame by screws 17.

The end wall 10a of the casing 10 which faces 15 the keeper 14 recedes to some degree in an inward direction, the face of the keeper being designed accordingly. While this is not a novel feature, the purpose of it is to afford better clearance between the door and the keeper on 20 the closing movement of the door.

The casing 10 is formed with a pair of ribs or braces 18 in the center, these ribs being spaced to accommodate the lock bolt 19 between them. The latter is of sector shape, being vertically pivoted at 20 between the ribs 18 whereby to swing 25 between the full-line and dotted-line positions indicated in Fig. 4. Thus, when the bolt is in the advanced position denoted by full-lines, its periphery cooperates with a rib 21 of the keeper to prevent the door from being opened, so that this can only occur when the bolt is retracted to the dotted-line position. The bolt is backed by a spring 22 which advances the bolt when it has cleared the keeper. Thus, on the closing movement of the door, the bolt trips the keeper rib 21 like a latch, locking the door.

The control of the bolt from the inner side of the door is usually accomplished in conventional panic locks by a vertical lever carrying a push plate. Thus, the design of the lever must be adapted for the right-hand and left-hand positions of the lock, as contemplated in an earlier section, making it necessary to carry two types of locks or levers in stock.

45 In order to render the instant lock adaptable to either the right-hand or left-hand position of a door, I have designed the control lever 23 to extend in a horizontal direction from the lock casing, developing the lever into an oval push plate 24 whose instruction is legible at either position of the lock as indicated in Figs. 1 and 2.

The lock casing 10 also has a pair of posts 25 in the region of the lever 23, these being vertically spaced to receive between them a hub 26 forming an enlargement of the lever. The hub is ver-

tically pivoted between the posts 25 on a pin 27, and it is inwardly extended toward the base of the casing with a pawl 28.

The pawl 28 of the lever 23 is normally behind a back flange 29 extended from the shank 30 of the bolt 19. Thus, when the push plate 24 is pressed from the full-line to the dotted-line position of Fig. 4, the pawl 28 impinges upon the back flange 29 of the bolt to retract the same, the changed positions of the affected parts being indicated by dotted-lines.

In the original form of the lock, the casing base 11 has an inward lug 31 to form a back stop for the bolt; and the casing receives a cover 32 to match the keeper 14 and provide a receptacle 33 for the remote end of the spring 22. The cover 32 is secured to the casing by screws or other suitable means indicated at 34.

It will be evident from the above description that I have provided a panic lock construction which enables one form of lock to be employed for either a right-hand or left-hand closing door, the change from one position to the other requiring only the turning of the lock to inverted position and no adjustments or replacements. Further, the control of the lock bolt is accomplished by a simple, double-lever action, which translates the forward or pressing movement of the push plate 24 into a lateral pivoting movement of the bolt 19. Thus, the described form of the lock has only two principal moving parts of solid construction, making it economical to produce and durable over a long period of use.

The modification of Figs. 5 to 8 deals primarily with the original form of the lock, but includes two features generally found in key-controlled doors. One of these features is an optional key-control to enable the door to be opened from the outside; and the other is a dogging device to keep the door in an unlocked condition.

For the key-control, the cover 32 is formed with a cavity 36, and the casing base 11 is perforated at 37 in registration with the cavity to journal a horizontal post 38. The base of the latter seats in the perforation 37 and contains a narrow slot 39 into which extends the tail piece 40 of a conventional cylinder lock 41, operated by a key 42. The object of the post 38 is to enable the bolt 19 to be retracted from the outside of the door by the manipulation of the key 42. For this purpose the post carries an oblique cam wing 43 which is adapted to enter behind the back flange 29 of the bolt when the key 42 is rotated to move the cam wing from the full-line to the dotted-line position of Fig. 5, or in the direction of the small arrow there shown. The back flange 29 is thus crowded against the spring 22 and retracts the bolt.

The dogging device is intended to retain the bolt in the retracted position in case the door is to be kept unlocked temporarily. It is in the form of a post 45, with ends journaled in the cover and casing base as indicated at 46. Near the base the post 45 has a lateral spur 47; and the opposite end of the post is flush with the outside of the cover, such end containing a key slot 48. Thus, when the dogging device is inactive, the position of the spur 47 is at one side of the working parts in the center of the lock, as indicated by full-lines in Figs. 5 and 6. However, when the dogging device is to be applied, the push plate 24 is advanced to swing the pawl 28 and retract the bolt as indicated in Fig. 8. A special key to fit the slot 48 is now inserted in

the post 45 and operated to turn the same and locate the spur 47 in the dotted-line position of Fig. 5. Fig. 8 shows that the spur is now behind the pawl 28, locking the same in the advanced position, so that the bolt is maintained in the retracted position.

It is now apparent that the novel lock can be made either plain or with the additional service features described, all without adding external parts or affecting the simple structure and operation of the main working parts or the universal application of the lock.

While I have described the original and modified forms of the invention along specific lines, various minor changes and refinements may be made without departing from its principle, and I desire to consider all such changes and refinements as coming within the scope and spirit of the appended claims.

I claim:

1. A lock for emergency doors comprising a casing, a latch bolt therein and retractable to permit the door to be opened outwardly, the action of the bolt being on a vertical pivot, a push plate opposite the inner side of the door, a substantially-horizontal lever extending from the push plate into the casing, and means between the lever and the latch bolt to swing the same in the retracting direction when the push plate is pressed toward the door, said means comprising a vertical pivot for the lever in the casing, a pawl extended from the lever beyond the pivot, a back flange of the latch bolt in front of the pawl, the pressure of the latter on the back flange procuring the retractive swing of the latch bolt, and a spring directed to the front of the back flange to resist said retractive swing.

2. In a lock for emergency doors, a casing, a latch bolt therein and retractable by swinging action on a vertical pivot, a back flange extended from the latch bolt, a lever pivoted vertically in the casing and extended with a pawl, the swing of the lever in a given direction causing the pawl to impinge on said back flange and secure said swinging action of the latch bolt, a horizontally-pivoted post alongside the back flange, and an oblique cam carried by said post, the rotation of the post to advance the cam crowding the latter against the back flange and securing the retraction of the latch bolt.

3. The structure of claim 2, said casing being mounted on a door with a cylinder lock, and said post having a receptacle for the tail piece of the cylinder lock to procure said rotation from the cylinder lock key.

4. In a lock for emergency doors, a casing, a latch bolt therein and retractable by swinging action on a vertical pivot, a back flange extended from the latch bolt, a lever pivoted vertically in the casing and extended with a pawl, the swing of the lever in a given direction causing the pawl to impinge on said back flange and secure said swinging action of the latch bolt, a horizontally-pivoted post alongside the back flange, and a side projection carried by said post, the post being rotatable to crowd the projection against the back of the pawl and lock the latch bolt in the retracted position.

5. The structure of claim 4, said post having its outer end exposed through the front of the casing, and such outer end being slotted to receive a special key for the rotation of the post.
